UNITED STATES PATENT OFFICE.

RUSSELL G. THOMPSON, OF ROCHESTER, NEW YORK, ASSIGNOR, BY MESNE ASSIGNMENTS, TO NORTH EAST APPLIANCES INC., A CORPORATION OF NEW YORK.

POWER MECHANISM.

Application filed January 5, 1925. Serial No. 727.

This invention relates to power mechanism suitable for actuating the type-bars or other parts of a typewriter or similar machine.

The object of the invention is to produce a simple, effective and compact mechanism for the purpose in question, which shall be capable of long use without undue wear.

To this end, the invention consists in the mechanism hereinafter described, as it is 10 defined in the annexed claims.

In the accompanying drawings, Fig. 1 is a side-elevation, partly in section, of power mechanism embodying the present invention, and Fig. 2 is a partial end-elevation, showing 15 particularly the cam and its controlling devices.

The invention is illustrated as embodied in power mechanism for actuating the type-bars of a typewriter. Fig. 1 indicates the 20 platen 5 of such machine, and shows one of the type-bars 6 of ordinary form. This type-bar is thrown into operation under the control of a key 7. It will be understood that the type-bar is one of the usual set or 25 series, and the key 7 is one of the usual set constituting the complete keyboard of the machine.

The power for actuating the type-bar is derived from a roller 8, which is rotated 30 constantly by any suitable source of power, such, for example, as an electric motor. This roller cooperates with a cam 9, consisting of sheet-metal and provided with a beveled periphery 10. The roller is provided with a series of annular beveled 35 grooves, each groove being in line with the edge of one of the cams. The cam, as shown, has two similar lobes, and performs a half-rotation at each cycle of operation. It turns 40 on a pivot 11 at the lower end of a power-lever 12. This lever comprises two sheet-metal side members, which are spaced apart at their lower end to receive the cam, and the side-members are connected by a pivot 45 13, about which the lever swings. It will be understood that when the cam is in rolling engagement with the power-roller 8 it has the effect of swinging the power-lever about its pivot.

50 The movements of the cam are controlled by mechanism including a spring device for initiating the rotary movement by which the cam is brought into engagement with the roller. For this purpose, the cam is provided with two diametrically opposite pins

14, which cooperate with an arm 15. This arm turns upon a pivot 16, between the side-members of the power-lever, and it is controlled by a spring 17, coiled about the pivot and engaging a lug 18 near the upper end of the spring-arm 15. In the normal inoperative position of the cam, in which it is slightly out of engagement with the roller, the spring-arm presses against which ever one of the pins 14 may be in the lower position, 60 as shown in Fig. 1, so that if the cam be released the arm causes it to turn sufficiently to bring its upper lobe into operative engagement with the grooved surface of the power-roller. 65

The cam is normally restrained from rotation by means of stop-mechanism controlled by a key 7. This mechanism comprises a stop-lever 19, which swings about the pivot 16 and is provided, at its lower end, with 70 two stop-lugs 20 and 21. The cam is provided with two detents 22 which cooperate with the stop-lugs. Normally, one of the detents engages the lug 20, as shown in Fig. 1. The upper end 23 of the stop-lever is 75 connected, by a rod 24, with a bell-crank lever 25 upon which the key 7 is mounted. This lever turns on a stationary pivot 26, and it is held in the normal position, shown in Fig. 1, by a spring 27. At this time a 80 laterally bent lug at the upper extremity of the stop-lever engages the edge of an opening in one of the side members of the power-lever, as shown in Fig. 1. When the key is depressed the stop-lever is swung in a direction to move the lug 20 out of the path of movement of the detent 22, whereupon the spring-arm turns the cam as above described, and the cam performs a half-rotation and 85 swings the power-lever. At the end of this 90 half-rotation the cam is arrested by the engagement of the second detent 22 with the stop-lug 21, since the half-rotation of the cam takes place before the operator can release the key. Upon the subsequent release and rise 100 of the key, the lug 21 disengages the detent, but the detent is arrested, after a slight turning movement of the cam, by the lug 20, the parts being thus brought back to the normal 105 position of Fig. 1.

The pivot 13 turns in a bearing-member 28, which is supported by a cross-bar 29 on the frame of the machine. A screw 30, threaded into the bearing-member, secures the latter in place. In first assembling the 110

machine, or in readjusting it, it is desirable that the normal clearance between the cam and the power-roller be exactly adjusted, and as a convenient means for performing this function, provision is made for adjusting the bearing-member horizontally upon the cross-bar 29. For this purpose an adjusting screw 31 is threaded into the bar, and is provided with a flange engaging a notch in the 10 lower surface of the bearing-member. The opening in the cross-bar, through which the screw 30 passes, is made large enough to permit the necessary lateral movement when the screw is loosened. The bearing-member 15 is provided with a stop-lug 32 which is normally engaged by the power-lever, and which determines the position of the lever relatively to the bearing-member. It will be evident, therefore, that by adjustment of 20 the bearing-member the clearance between the cam and the roller may be exactly determined.

Where a type-bar or other part is actuated by a cam-operated lever of the type in question, it is desirable that pressure between the cam and the roller be maintained throughout the operative motion, so as to insure the continued rolling action of the cam and prevent it from slipping or from jumping out 25 of engagement with the roller. This is particularly the case where the engaging surfaces of the cam and roller are of metal or other material having a relatively low coefficient of friction. Accordingly, a feature 30 of the present invention resides in the use of a spring 33 which is attached, at one end, to the power-lever and at the other end to a lug on the bearing-member. This spring insures a steady frictional engagement between 35 the cam and the roller throughout the cycle 40 of operation of the cam.

A feature of the invention resides in a simple and direct mode of connection between the power-mechanism and the type-bar. In previous power-mechanisms of the cam-and-roller type it has been the practice so far as the inventor is informed, to extend the power-lever in a generally horizontal direction, and to connect it with a type-bar 45 through the intermediation of some system of levers or links. In the present construction, however, the power-lever is extended upwardly from its pivot, to a length sufficient to give the necessary extent of a motion, and is connected, at its upper end, directly with the short arm of the type-lever, by means of a pull-rod 34. If these pull-rods be made of sufficient length, such direct connection is practical and permissible, regardless of the fact that the type-bars are 50 pivoted on the usual segment and that this results in somewhat varying angles in the pull-rods.

In order that the spring 33 may have the 55 intended result, it is necessary to prevent

the type-bar, or other actuated member, from acting, during any part of its operative motion, to pull the cam away from the roller through the effect of the momentum gained during the early part of its motion. Accordingly some provision should be made for lost motion between the parts. In Fig. 1 accordingly, the rod 34 is shown engaged in an elongated opening 35 in the upper end of the power lever. This permits the type-bar to overrun slightly and to complete its operative stroke while the cam is still maintained in engagement with the roller by the spring 33, and without necessity of very exact adjustment of the mechanism.

It will be apparent that the effect of the beveled periphery of the cam, and the corresponding groove in the power-roller, is to create sufficient frictional engagement between these parts to insure against slippage when they are rolling together, and that the use of metal such as hardened steel in these parts is thus made permissible, whereby a considerable degree of durability is secured. The cam mechanism, the power-lever, the bearing-member and the spring 33 constitute a convenient unitary assembly which may be readily mounted in the machine or removed therefrom for the purpose of repair or replacement. The direct connection between the power-lever and the type-bar greatly simplifies and lightens the operating mechanism, and permits rapid and positive action of the type-bars.

The invention is not limited to the embodiment thereof, hereinafter described and illustrated in the accompanying drawings, but it may be embodied in various forms within the scope of the following claims.

The invention claimed is:

1. Power mechanism, for a typewriter or the like, comprising: a constantly rotary power roller; a power lever; a cam carried by the power lever and cooperable with the power roller; a bearing-member, on which the power lever is pivoted, provided with a stop cooperating with the power lever to determine its normal inactive position; a spring, connecting the power lever and the bearing-member, tending to swing the power lever in the direction of said stop; connections, between the power lever and the part of the machine which is to be actuated, having provision for lost motion; and means for turning the cam into engagement with the power roller.

2. Power mechanism, as in claim 1, in which means are provided for adjusting said bearing-member towards and from the power roller.

3. Power mechanism, for a typewriter or the like, comprising: a constantly rotary power roller, a power lever, a cam rotatably mounted on the power lever and cooperable with the power roller, the cam having an

increasing radius so that when freely rotating in engagement with the roller it causes a swinging movement of the lever, a spring connected with the power lever and tending to swing it in the direction to move the cam bodily toward the roller, a stop for limiting the movement of the lever by the spring, means for turning the cam into initial engagement with the roller and for

arresting its turning movement at each operation, and connections, between the power lever and the part of the machine to be actuated, having provision for lost motion to permit said part to overrun the power mechanism without causing disengagement of the cam from the roller. 10 15
